DESIGN FOR A PNEUMATIC TIRE

Bert Lee, Sacramento, Calif., assignor of one-half to Donald R. da Roza, Sacramento, Calif.

Application April 4, 1940, Serial No. 91,471

Term of patent 3½ years

To all whom it may concern:

Be it known that I, Bert Lee, a citizen of the United States, residing at Sacramento, in the county of Sacramento and State of California, have invented a new, original, and ornamental Design for a Pneumatic Tire of which the following is a specification, reference being had to the accompanying drawing, forming a part thereof.

In the drawing:

Figure 1 is a side elevational view of a pneumatic tire, partly in dotted lines, showing my new design; and

Figure 2 is a transverse sectional view thereof, partly in dotted lines.

The characteristic features of the design reside in a tire having white side walls with a plurality of concentric ribs thereon, the ribs being colored black.

I claim:

The ornamental design for a pneumatic tire, as shown and described.

BERT LEE.
